MANHOLE, SEWER, OR OTHER CONDUIT AND METHOD OF CONSTRUCTING THE SAME.

1,144,468.

Specification of Letters Patent. Patented June 29, 1915.

Application filed November 12, 1914. Serial No. 871,683.

To all whom it may concern:

Be it known that I, CHARLES H. FROST, a citizen of the United States, residing at Pasadena, in the county of Los Angeles and State of California, have invented certain new and useful Improvements in Manholes, Sewers, or other Conduits and Methods of Constructing the Same, of which the following is a specification.

10 This invention relates to methods of building man holes, sewers, or other conduits.

In my co-pending application Serial No. 863,426, filed September 25, 1914, I have described and claimed an improved form of brick tapering or wedge-shaped in cross-section and having a longitudinal rib on one side and a longitudinal groove upon the other side, whereby when the bricks are laid side by side in mortar to form a circular sewer or man hole they will interlock one with the other, and be held rigidly together against the strains to which they are subjected, arising from the weight of the bricks, and the pressure of the surrounding earth.

25 In building a man hole it is the usual practice to start at the bottom with a circular course of bricks and build up the structure for, say, about four feet in height for a given diameter, as for example four feet 30 in diameter. Thence the man hole is built up of gradually diminishing diameters, tapering up to two or three feet at the top, the depth of these man holes varying in different locations, according to the topography 35 of the ground. Man holes which have been heretofore constructed in this manner, of common solid building brick, required two rings of such bricks to every course, in order to be sufficiently rigid to withstand the 40 strains against the walls of the man holes, whereas with hollow interlocking bricks of the character disclosed in my prior application above referred to, sufficient rigidity of the walls has been effected by using a single row or ring of bricks at each course.

45 This results in an enormous saving in the number of bricks required to build a man hole with the brick of my said application as compared with the number of common 50 bricks which were required under former practices. In building the tapering portions of these man holes, where the diameter is progressively diminished as the height increases, I have discovered that tapering 55 bricks having the standard measurements at its two side edges (as for instance 3 inches

at its widest edge and 2½ inches at its narrowest edge) are unsuited, if used alone, for building a progressively tapering man hole; but by introducing therewith a suitable 60 number of preformed tapering bricks, known as "filler bricks", whose inner or narrowest edges are less in width, compared with the width of their outer or wider edges, than the standard brick of the dimensions 65 above-referred to, a man hole of gradually decreasing diameter may be built up. The number of these filler bricks that are introduced in the successive courses, in proportion to the standard bricks, will depend upon 70 the diameter of the man hole, and the proportionate number will be gradually increased as the man hole decreases in diameter. In practice it is found that bricks having the standard measurements, or the lesser 75 degree of taper from their wider to their narrower edge, as above referred to may be used exclusively to build up the cylindrical portion of the man hole, for a distance of 4 feet, for instance, to the point where the 80 man hole begins to taper. From this point upward to the smallest diameter the "filler bricks" will be introduced in increasing numbers at each course, and at the point of smallest diameter, which may be 2 feet, there 85 will be employed an equal number of standard, and filler bricks, arranged alternately, one with the other, in the final circular course of the man hole.

The mode of constructing a tapering conduit in the manner above specified, whereby a gradually diminishing or tapering structure is produced by using bricks which have been previously made of two degrees of taper, constitutes the important 90 feature of my method.

Another important feature of the invention comprises a filler brick, wedge-shaped or tapering in cross-section, and provided in one side with an enlarged groove, and on its other side with a relatively diminished rib which tapers from its base outwardly, the angles of union of the walls of said groove and rib with the side walls of the brick presenting curves instead of sharp 100 angles. The advantage of thus forming the ribs and grooves is that the rib has additional strength by reason of its widened base, and by making the groove sufficiently 105 larger than the rib, opportunity is presented for swelling of the rib when the brick is released from the die, and also for the groove 110

to be slightly diminished from the pressure exerted by the bricks in the kiln, without preventing proper registry and interlocking of the ribs and grooves when the bricks are laid side by side to form a man hole.

These, and other important features of the invention will be more particularly described and claimed.

In the drawings: Figure 1 represents a vertical sectional view of a man hole which has been constructed in accordance with the present invention; Fig. 2 is an enlarged sectional plan view, on the line 2—2, Fig. 1, showing a portion of a circular course of the two kinds of bricks, laid in accordance with this method; Fig. 3 is a transverse section of the standard brick, and Fig. 4 is a transverse section of the filler brick.

The man hole illustrated in Fig. 1 comprises a cylindrical portion 2, which, as is usual in such structures, is built up of successive courses to the desired height, and thereafter the courses of bricks are progressively reduced in diameter as the man hole tapers from the cylindrical portion upward to the top course of bricks which is located at or near the surface of the ground. In building such a man hole under my invention I preferably use for the cylindrical part 2, my tapering, interlocking brick as described in my co-pending application above referred to. These bricks may be 3 inches at their widest edge, and taper slightly to their narrow edge, which may be $2\frac{1}{2}$ inches wide. The bricks are provided upon one side with a longitudinal rib, and upon the opposite side with a longitudinal groove which is larger than the rib in order to allow for the necessary amount of mortar between the edges of the bricks, and in the grooves surrounding the ribs, so that when the bricks are laid side by side to form the circular courses the ribs and grooves will interlock, and hold the bricks rigidly together, and prevent relative sliding movement of the bricks in the planes of their adjoining faces. After a suitable number of courses have been laid, of uniform diameter, to build the cylindrical part of the man hole to the required height, as for example 4 feet, in a man hole whose smallest diameter is 2 feet, the courses which progressively diminish in diameter are added. For these courses a brick having the slight amount of taper of my standard interlocking brick, as above specified, could not be used exclusively, and produce a regular, and gradually diminishing taper in the circular walls of the man hole. At this point in the construction I, therefore, introduce a suitable number of the filler bricks 3 one of which is shown in plan in Fig. 4. These bricks are formed tapering, from their widest edge to their narrowest edge, but such taper is increased as compared with the

taper of the standard brick, and for practical purposes I have found that a filler brick, whose widest edge, $a-b$ is $3\frac{1}{4}$ inches, should at its narrowest edge $c-d$, be approximately $1\frac{1}{2}$ inches. The groove 6 in the side wall of this brick is, as shown, "eased off" or rounded so as to present smooth curves where its wall joins the side of the brick, and the rib 8 on the opposite side is similarly "eased off" or curved where its sides join the side wall of the brick, so as to merge into the latter. The base of this rib is also made thicker than its outer end portion, so that the rib is wedge-shaped, and this has been found to increase the strength of the rib. When these bricks are released from the die in which they are formed there is a tendency for the ribs 8 to swell and increase in size, and it is also a fact that the grooves 6 are frequently diminished in size by the pressure exerted on the bricks when they are stacked in the kiln. For these reasons it is important that the grooves should be of substantially larger size than the ribs, and by thickening the base of the ribs strength is added, and the danger of ribs being distorted or sheared off is materially reduced. These bricks are provided with openings 10, 12, for the purposes of rendering the bricks lighter, and freely admitting the heat to the interior of the bricks while they are being burned with a view to having the burning operation equalized throughout the brick, all as set forth in my co-pending application. In the filler brick herein described the size of these openings has been reduced somewhat, and as the end $c-d$ of the filler bricks is so narrow it has been found expedient to form the hole 10 near this end of the brick of circular form, as this gives the best results.

In building a manhole of the type shown in Fig. 1, the cylindrical portion is first formed by laying a suitable number of circular courses of bricks, all of the standard size and having the same degree of taper, with each circular course of the same diameter, until the desired height is reached. From this point upward the courses of progressively decreasing diameters are laid to make the tapering portion of the manhole. On the top course of the section 2, a mortar joint 13, wedge-shaped in cross-section, having its thickest part at the outer side of the manhole and tapering to a fine edge at the inside, is laid. This forms a base for the tapering portion of the man hole, and causes the bricks of each of the superimposed courses, and which are of successively diminishing diameters, to lean or tilt inwardly toward the center. The first course of the tapering portion 4 is made up of a number of the standard bricks, together with a suitable number of the filler bricks, or those of the greater degree of taper, and the diam-

eter of each, successive circular course is diminished by increasing the number of the 5
filler bricks that are used in proportion to the number of the standard pricks until
the smallest diameter desired is reached. In
10 the final course it has been found that the
filler bricks may be used in equal number
with the standard bricks, and the two kinds
of bricks are placed alternately, first one
15 and then the other, throughout the course.
The inclination of the base 13, which causes
the bricks to tilt inwardly, together with
the progressive and regular decrease in the
size of each successive circular course of
20 bricks results in the production of a struc-
ture having a smoothly tapered and an even
and regular outer surface. By referring to
Fig. 2, which shows a portion of one course
of bricks used in the production of the
25 tapering section 4, the difference in taper
between the standard bricks 1 and the filler
bricks 3, will be readily seen. The dotted
lines which are projected as extensions of
the sides of the standard bricks form sec-
tors of a larger circle than the circle of
which the sectors formed by extending the
sides of the filler bricks form parts.

While I have, throughout this specification, referred to the bricks having the lesser 30
degree of taper, from end to end, as the
"standard" bricks, and to the bricks having
the greater degree of taper, from end to end, as the "filler" bricks, it is to be
understood that both of these bricks are
35 standard in a sense, that is, each brick is
pre-formed, and is produced in great quantities
with its desired degree of taper, although
the so-called "filler" bricks are formed
40 with the decidedly increased amount
of difference between the length of inner
and outer edges, as compared with the
standard brick. In order to distinguish
these two kinds of bricks from each other,
however, I shall, in the claims, employ the
45 terms "standard" and "filler", in the senses
herein explained.

While I have described my invention as
relating to certain improvements in man

holes and methods of constructing the same, 50
it is to be understood that the invention is
not necessarily limited to man holes, but
the method of construction and the elements
heretofore described may be employed, if
desired, in sewers, or other conduits of cir-
55

Having thus described my invention what
I claim and desire to secure by Letters Pat-
ent of the United States is:

1. That improvement in methods of pro-
ducing a tapering man hole, conduit, or 60
similar structure, which comprises provid-
ing a suitable number of pre-formed stand-
ard bricks having a given taper from their
inner to their outer edges, and a suitable
number of pre-formed filler bricks, having a 65
greater degree of taper, laying successive
courses of decreasing diameters by using a
suitable number of said standard bricks,
with a number of said filler bricks at spaced
intervals in each course, and increasing the 70
number of filler bricks in proportion to the
number of standard bricks used as the diam-
eter of the structure decreases.

2. That improvement in methods of pro-
ducing a tapering man hole or similar struc- 75
ture, which comprises providing a number
of pre-formed standard bricks having a
given taper from inner to outer edges, and
a number of pre-formed filler bricks hav-
ing a greater degree of taper, laying a suit- 80
able number of said standard bricks side by
side with a suitable number of filler bricks
to form a circular course, and continuing
the structure by adding successive courses
of decreasing diameters, each added course 85
containing a greater proportionate number
of the filler bricks, until the course of small-
est diameter is laid to complete the struc-
ture.

In testimony whereof I affix my signature 90
in presence of two witnesses.
